CHARLES R. SEYMOUR, OF ROCHESTER, NEW YORK, ASSIGNOR TO M. D. KNOWLTON COMPANY, OF ROCHESTER, NEW YORK, A CORPORATION OF NEW YORK.

SLOTTING MACHINE.

Application filed December 3, 1925. Serial No. 72,857.

This invention relates to certain improvements in the slotting machine as disclosed in the application of Chester B. Pearsall, filed July 15, 1925, Serial No. 43,786, said 5 improvements comprising a special form of slip gear interposed in the driving train to permit the independent rotary adjustment of the lower cutters to bring the zero points of the cutters into registry with the middle 10 line of the sheet to be slotted, and also comprising means for adjusting the respective pairs of lower and upper cutter knives longitudinally of their supporting shafts to effect 15 the slotting of sheets and blanks of varying widths.

In the accompanying drawings:

Fig. 1 is a side elevation of a slotting machine embodying the invention.

Fig. 2 is a broken plan view of the machine.

Fig. 3 is a broken front elevation of the machine.

Fig. 4 is a vertical longitudinal section of the machine.

Fig. 5 is an enlarged sectional side elevation of two of the rotary cutters, on the line 5—5 of Fig. 6.

Fig. 6 is a vertical longitudinal section through the cutters.

Fig. 7 is a broken side view of the main member of the lower cutter.

Fig. 8 is an enlarged side elevation of the slip gear and its coacting parts.

Fig. 9 is a section on line 9—9 of Fig. 8.

Fig. 10 is a sheet comprising four blanks slitted and creased longitudinally by a slitting and creasing machine, preparatory to entering the slotter of the present invention.

Fig. 11 shows the sheet immediately after 40 entering the slotter with the transverse creases and the left edge slots partly formed.

Fig. 12 shows the transverse creases nearly completed, the left edge slots finished and the center slots nearly finished.

Fig. 13 shows the sheets with the left edge slots and the center slots completed and the right edge slots started.

Fig. 14 shows the completely slotted sheet ready for breaking apart into four box blanks.

As generally described, the slotting machine is constructed and designed to receive sheets of pasteboard, corrugated board, or the like, from a slitting and creasing machine of standard type, which slits and

creases the sheet to define the margins of one or more blanks and to crease the sheet along the lines of the folds or bends of the blank or blanks, the slitted and creased sheets being fed to the slotting machine by 60 suitable feed rollers and passed between co-operating pairs of rotary knives or cutters mounted upon shafts disposed one above the other and adjustable longitudinally of the shafts to accommodate blanks or sheets of 65 different widths, the lower cutters being provided with circumferentially adjustable arc-shaped knives, which cooperate with the annular knives of the upper cutter to excise 70 slots in the front and rear edges and the intermediate portion of the sheet, as particularly described in the application aforesaid

The shaft 30, which supports the lower rotary slotters, is journaled in bearings in the side members of the frame 10 and has 75 the lower rotary cutters secured thereto in sets of three for individual longitudinal adjustment with respect to the shaft. The structural and operative details of the lower rotary cutters are illustrated more particularly in Figs. 4, 5, 6 and 7. The body portion of each cutter comprises a hollow hub-like casting 50 having a peripheral flange 52 and a threaded shoulder 51, with an annular recess 50' formed in the face of the flange 80 52 adjacent the threaded shoulder 51. Co-operating with the threaded shoulder 51 is a clamping ring 54 having an annular recess 55 corresponding to recess 50' in the member 50, and a flat face paralleling the 85 inner face of flange 52 and serving to clamp the interposed knives rigidly in position, when ring 54 is set up. Mounted for peripheral adjustment on the shoulder 51 of the hub section 50 are four knives 56, 57, 58 90 and 59, which extend beyond the peripheral edge of the hub 50, said knives comprising relatively thin arc-shaped blades, the peripheral edges of which constitute the cutting or excising elements, the successive blades overlapping each other, as shown in Figs. 5 and 6, and being clamped firmly in adjusted relation between the flange 52 on hub section 50 and the clamping ring 54. The several 95 arc-shaped knives are provided on their inner rim with arcuate racks 56', 57', 58' and 59', respectively, riveted thereto, the racks on overlapping knives being disposed on opposite sides, and operating in the recesses 50' in the hub section and in a corresponding 100

105 110 115

recess in the clamping ring. As indicated, the four knives are adjustable circumferentially of the supporting member 50 in order to operate upon sheets of different sizes, and to effect this circumferential adjustment simultaneously in all of the lower cutters, there are provided four shafts 62, which traverse corresponding openings 53 in each member 50, the several shafts preferably being square in cross section and engaging similarly shaped bores of bushings 60 journaled in the openings 53, each bushing carrying a gear or pinion 61 which meshes with the rack of the corresponding arc-shaped knife. These parts are so coordinated that by rotating a given shaft 62 by means of a suitable wrench, the corresponding knife will be moved peripherally of the hub section to effect the desired adjustment of the knife. In order to facilitate this adjustment, the rim of flange 52 of the hub section is provided with a scale marked in inches and fractions thereof, as indicated at 8, by means of which the exact position of the several knives may be determined.

The knives 56 and 59 are designed to cut the slots A and C in the forward and rear edges, respectively, of the sheet, as the latter is fed through the slotted, while the knives 58 and 57 operate to cut a single slot B in the middle of the sheet, and, as the width of the sheet is sufficient to form two blanks, each middle slot constitutes the slot in the right marginal edge of one blank and the slot in the left marginal edge of the adjacent blank. From the foregoing, it will be evident that the length of the center slots B will be determined by the distance between the points or ends of knives 58 and 57, as indicated in Fig. 4. In order to properly position the knives 58 and 57 to cut the proper length of slot B, the knives are adjusted so that their points or terminal edges lie equal distances from the zero point of the scale, as indicated in Fig. 4, and, as these distances are indicated in inches and fractions thereof on the scale, it is obvious that accurate setting of the knives to excise slot B of proper length may be effected readily. It will be apparent that the longitudinal center line of each sheet fed to the machine must register with the zero point of each of the lower cutters and special means are provided for effecting this relation for different widths of sheets, as will be hereinafter explained.

As knives 56 and 59 cut slots in the front and rear edges of the sheet, the setting of these knives to cut slots of the proper depth may be readily effected by reference to the scale on the peripheral edge of the hub 50, the scale reading in both directions from the zero point, as indicated in Fig. 4.

In order to adjust the lower cutters so that the zero points on the scales may be

brought into coincidence with the longitudinal center lines of sheets of varying widths, the shaft 30 carrying the lower cutters is provided with a special slip gear connection shown in Figs. 1, 3, 8 and 9, which admits of the rotary adjustment of the shaft and the cutters independently of the driving mechanism. Secured to the reduced outer end 32 of shaft 30 is a hub 33 having an annular shoulder 34, upon which is mounted a gear ring 35, which meshes with gear 12 of the driving train. The ring 35 is normally locked to said hub 33 to drive the shaft 30 by means of bolts 38 passing through holes 36 in the hub section, said bolts having squared heads 39 engaging an annular T slot 37 formed in the ring 35. When the nuts 40 of the bolts 38 are set up, the gear ring 35 is clamped to the hub. When, however, the nuts are loosened, the T head ends of the bolts slide freely in the T slot and the hub and shaft 30 may be freely rotated independently of the gear ring 35. Approximately one-half of the periphery of the hub 33 is provided with gear teeth 41, which are engaged by a pinion 45 fast to a shaft 42 journaled in an opening 43 formed in the ring 35, the outer end of the shaft being squared to receive an operating crank. An angular bracket 44 bolted to the gear ring 35 is provided with an opening through which the shaft 42 extends and with a pointer or index 44', which registers with a scale (see Fig. 8) marked on the face of the hub 33 adjacent the teeth 41 thereon. By loosening the nuts 40 on the bolts 38, the gear ring and the hub may be independently rotated and by applying the crank to the squared end of shaft 42 and turning the latter in the appropriate direction, a relative rotatory adjustment between the hub 33 and the gear ring 35 may be effected to accommodate sheets of different widths, the proper adjustment being indicated by the pointer 44' on the scale, so that the zero points of the lower cutters will be brought into coincidence with the center line of the sheets. The scale on the hub 33 being graduated in inches, it will be apparent that the necessary adjustment may be readily effected. Said scale on the hub is graduated for sheets varying in widths from twenty-two inches to sixty-eight inches, the scale indication denoting the width of half the sheet. After the adjustment of the shaft 30 and the lower cutters 50 to accommodate the particular sheets to be operated upon, the nuts 40 are set up and the gear ring 35 is clamped to hub 33 in proper relation to rotate shaft 30 and the lower cutters in the normal operation of the machine.

The upper cutters correspond in number and relative position on shaft 80 with the lower cutters on shaft 30. Each of said upper cutters comprises a hub section 90,

keyed to shaft 80 for adjustment longitudinally of said shaft, preferably by a split wedge clamp such as is ordinarily used for fastening scoring or slitting knives to their supporting shafts. The hub 90 has a peripheral flange 91, which constitutes a clamping jaw, and the cylindrical portion of the hub adjacent the flange is provided with a screw threaded section 90' to receive 5 a threaded ring 93, which forms the second member of the clamp, between which ring and flange 91 are securely locked two annular knives 94, 94, which are separated by a spacer ring 95 of less diameter than the knife 10 rings and which leaves a space between the knives 94, 94 corresponding in width with the knives on the lower cutter. As indicated, the screw threaded ring 93 serves to clamp the knives 94, 94 and the interposed 15 spacer ring 95 against the fixed flange 91 on the hub, and the knives are locked in position by pins 97, which engage openings in the flange 91 and the ring 93.

Special means are provided for adjusting 20 the upper and lower cutters longitudinally of their supporting shafts to bring the knives into alignment with the creases in the blanks, so that the slots will be properly positioned with respect to the creases. 25 The adjusting means are carried by the individual lower cutter elements, so that, when the upper cutters are unlocked from clamping engagement with their supporting shaft 30 80 and the latter is lowered to bring the knives of the upper and lower shafts into interlocking engagement, the two sets of cutters may be simultaneously adjusted along their shafts. The adjusting means is illustrated in Figs. 4, 5 and 7 and comprises 35 the following instrumentalities:

Fitted in a seat in the shaft 80, which supports the lower cutters, is a key 70 which has an outwardly extending rib 71 which engages a similar seat in the hub member 50, the 40 outer face of said rib being provided with gear teeth which are properly fashioned to mesh with a worm 73 journaled on a shaft 72 mounted transversely of the hub casting 50, the worm 73 having connected therewith 45 a bevel-gear 74 which meshes with a bevel-gear 75 on the end of a shaft 76 mounted in a sleeve 78 formed integrally with the hub section, the end of the shaft 76 projecting 55 through an opening in the hub section and being provided with a squared wrench engaging portion 77, by means of which the shaft may be rotated, either by a hand wrench or by an electrically driven wrench. By rotating the shaft 76 in one direction or 60 the other, the corresponding lower knife will be adjusted longitudinally of its supporting shaft 80 by the engagement of the worm 73 with the rack 71 and the adjusting movement of the lower cutter will effect the correspond-

ing adjustment of the cooperating upper cutter, by reason of the engagement of the knives of the two cutters. After the desired adjustment of the several sets of cutters have been effected, the upper cutters are again locked in position on their supporting shaft 65 70 and the machine is again ready for operation.

From the foregoing description and illustration, it will be apparent that the machine is adapted to operate upon sheets of varying 75 lengths and widths for slotting multiple blanks comprised within a single sheet, the cutters of each set being adjusted to operate upon blanks of varying sizes by adjusting the cutters of each set longitudinally of their supporting shafts and by adjusting the knives of the lower cutters circumferentially of the hub-like holders therefor to cut the marginal slots of two blanks disposed transversely of the sheet at one operation, the intermediate knives of each lower cutter excising a slot in the mid section of the sheet, which slot, when the sheet is divided along its median line, constitutes edge slots 80 of adjacent blanks and the terminal knives of each lower cutter forming the slots in the front and rear edge of the sheet, which slots are complementary to the single slot formed by the intermediate knives. It will be seen, therefore, that a single machine is particularly adapted to accurately slot two, four or six blanks defined within the area of the sheet by the slitting and creasing machine and to deliver the slotted, creased and slotted 85 sheets in condition to be broken apart into individual blanks, which are ready for immediate folding and staying to constitute 90 complete boxes or containers.

What I claim is:

1. A blank slotting machine comprising 105 upper and lower shafts, rotary cutters on the upper shaft, rotary cutters on the lower shaft cooperating with the cutters on the upper shaft, each lower cutter including circumferentially adjustable knives for cutting slots in two blanks included within the width of a sheet, and means for driving the shafts, said means including a slip gear connected with the lower shaft whereby the latter may 110 be rotatably adjusted independently of the driving means.

2. A blank slotting machine comprising 115 upper and lower shafts, rotary cutters on the upper shaft, rotary cutters on the lower shaft cooperating with the cutters on the upper shaft, each lower cutter including circumferentially adjustable knives for cutting slots in two blanks included within the width of a sheet, a gear train for driving both 120 shafts, said train including a slip gear on the lower shaft, said slip gear comprising a hub fast to the lower shaft, a gear rim rotatable on said hub, bolts for locking the rim 125 .

to the hub, and means for rotating the hub and lower shaft independently of the gear train.

3. A blank slotting machine comprising upper and lower shafts, rotary cutters on the upper shaft, rotary cutters on the lower shaft cooperating with the cutters on the upper shaft, each lower cutter including circumferentially adjustable knives for cutting slots in two blanks included within the width of a sheet, a gear train for driving both shafts, said train including a slip gear on the lower shaft, said slip gear comprising a hub fast to the lower shaft, a gear rim rotatable on said hub, bolts for locking the rim to the hub, and means for rotating the hub and lower shaft independently of the gear train, said means including gear teeth on said hub, a pinion journaled on said gear rim engaging the teeth on the hub, and a crank engaging portion on the pinion journal.

4. A blank slotting machine comprising upper and lower shafts, rotary cutters on the upper shaft, rotary cutters on the lower shaft cooperating with the cutters on the upper shaft, each lower cutter including circumferentially adjustable knives for cutting slots in two blanks included within the width of a sheet, a gear train for driving both shafts, said train including a slip gear on the lower shaft, said slip gear comprising a hub fast to the lower shaft, a gear rim rotatable on said hub, bolts for locking the rim to the hub, and means for rotating the hub and lower shaft independently of the gear train, said means including gear teeth

on said hub, a shaft journaled on said gear rim and having a crank engaging end, a bracket fixed to said gear rim through which the shaft extends, said bracket having an index pointer on its end, a pinion on said shaft engaging the teeth on the hub, and score markings on the hub cooperating with said pointer.

5. A blank slotting machine comprising upper and lower shafts, cooperating rotary cutters on said shafts, each cutter including a hub and coordinate knife elements, and means for adjusting the individual cutters longitudinally of the supporting shaft, said means including a rack secured longitudinally of the shaft, a worm journaled in the cutter hub and engaging said rack, and means carried by the said hub for operating said worm.

6. A blank slotting machine comprising upper and lower shafts, cooperating rotary cutters on said shafts, each cutter including a hub and coordinated knife elements, and means for adjusting the individual cutters longitudinally of the supporting shaft, said means including a rack secured longitudinally of the shaft, a worm journaled in the cutter hub and engaging said rack, a bevel-gear secured to said worm, a shaft journaled in a transverse bearing in said hub and having a wrench engaging portion on its outer end, and a bevel-gear on the inner end of said shaft meshing with the bevel-gear associated with said worm.

In testimony whereof I affix my signature.

CHAS. R. SEYMOUR.
